J. S. CALDWELL.
FLUSH TANK SUPPLY VALVE.
APPLICATION FILED JULY 12, 1907.

913,808.

Patented Mar. 2, 1909.

UNITED STATES PATENT OFFICE.

JAMES S. CALDWELL, OF KANSAS CITY, MISSOURI, ASSIGNOR OF ONE-HALF TO FRANK M. JACKSON, OF KANSAS CITY, MISSOURI.

FLUSH-TANK SUPPLY-VALVE.

No. 913,808.

Specification of Letters Patent.

Patented March 2, 1909.

Application filed July 12, 1907. Serial No. 383,524.

To all whom it may concern:

Be it known that I, JAMES S. CALDWELL, a citizen of the United States, residing at Kansas City, in the county of Jackson and State of Missouri, have invented certain new and useful Improvements in Flush-Tank Supply-Valves, of which the following is a specification.

This invention relates to flush-tank supply valves, and my object is to produce a device of this character in which the valve closes with the pressure; which is equipped with all-metal all-ground seats to avoid the necessity of frequent repair, which embodies an inverted seat, and a knife-edge cup to engage said seat for the purpose of preventing sand and other foreign substances in the water from interfering with the proper engagement of said cup with said seat.

A still further object is to produce a valve which operates efficiently and reliably and which is of simple, strong, durable and inexpensive construction and to which access may be easily and quickly had for any purpose.

With these objects in view the invention consists in certain novel and peculiar features of construction and organization as hereinafter described and claimed; and in order that it may be fully understood reference is to be had to the accompanying drawings, in which:—

Figure 1, is a plan view of a part of a flush box equipped with a valve embodying my invention. Fig. 2, is a central vertical section taken on the line II—II of the same. Fig. 3, is an enlarged horizontal section taken on the line III—III of Fig. 4. Fig. 4, is a central vertical section taken on the same line as Fig. 2, but on the scale of Fig. 3.

In the said drawings 1 indicates a flush box of the usual or any preferred type and 2 a water supply pipe for the same. The valve casing is in two parts, the upper part, 4, having outwardly projecting lugs 5 through which screws 6 extend to secure it to the tank. The said upper part is provided with a vertical passage 7 in its upper end and with a spout 8 connecting with the interior of said part below said upper end.

9 is a valve-seat-casting onto which the upper and lower parts of the casing are screwed or otherwise secured. This casting which is in the form of a threaded cylinder is provided with a central cylindrical portion

10, the passage of said portion being ground to insure a perfectly smooth wall and being of uniform diameter throughout, said wall at a suitable point being provided with an opening 11. Above said opening the wall is of increased thickness the thicker portion being beveled downward and outward at its lower end to provide an inclined downwardly-disposed annular seat 12, the lower portion of the wall being ground externally in order to fit with a water-tight relation into a cup 13 formed integral with or secured to the lower end of a valve plug 14, the securing means shown being a screw-bolt 15. The valve plug 14 is ground into perfect cylindrical form to fit with a water-tight relation in the passage of the cylindrical portion 10. The plug is cast with or otherwise secured upon the lower end of a vertical valve-stem 16, and secured upon the upper end of said stem with a screw-thread relation, as shown or otherwise, is a cylindrical head 17 for said stem, the head being provided with upwardly projecting ears 18.

19 indicates lugs on the upper part of the casing and pivoted to and between said lugs is a bell-crank lever 20 having a float 21 at its outer end and connected by a toggle-joint with a pair of lugs 22 also cast with the upper part of the casing, the toggle-joint comprising links 23 and 24 and being connected pivotally at its middle with the lugs 18 by a link 25.

When the tank is charged with water as shown in Fig. 2—the water which is in the casing being omitted from the drawing to avoid obscuring the same in any part—the float is elevated and, through the connections described, holds the valve elevated with the beveled or knife edge upper end of the cup engaging the downwardly disposed seat 12 and the plug 14 closing opening 11. When the water is permitted to flow from the tank, the float falls and in such action tends to straighten the toggle and force the valve downward. The continued downward movement of the float results in unseating the plug and cup at about the same moment, and as this occurs the water under pressure, rushes from the lower part 3 of the casing over the cup and through opening 11 above the plug, and then passes up into the chamber of the upper part 4 of the casing and escapes thence into the tank, it being understood that the water moves at suf-

ficient speed and in sufficient volume to recharge the tank to the required depth, when the float reseats the plug by causing it to recover opening 11 and the cup by the re-engagement of its beveled or knife-edge upper end with the downwardly disposed seat 12. It will thus be seen that this valve provides a double seal against the entrance of water into the tank so that there shall be no possibility of a volume of water entering the tank sufficient to overflow therefrom. It will also be apparent that access may be had to the valve or valve casting by screwing the lower part 3 of the casing down onto pipe 2 until it is disengaged from said valve casting, when it may slide down further upon said pipe and clear the casting, the threaded portion of the inlet pipe 2 being of greater external diameter than the smooth portion of the same, as indicated in Fig. 2. The valve casting may then be screwed downward until it is disengaged from the upper part of the casing, it being obvious that before the casting can be thus manipulated, the cup 13 must be detached from the plug 14. The latter may be removed by withdrawing the pivot connecting the members of the toggle and then pulling the valve with its head and stem up through the upper part of the casing. It will thus be seen that the entire valve can be practically dismantled without disturbing the upper part of the casing or the float, and that said parts can be reassembled by reversing the operations described.

From the above description it will be apparent that I have produced a valve for flush tanks which embodies the features of advantage enumerated as desirable in the statement of the object of the invention and while I have illustrated and described its

preferred embodiment, it is to be understood that I reserve the right to make such changes as properly fall within the spirit and scope of the appended claim.

Having thus described the invention what I claim as new and desire to secure by Letters Patent, is:—

A supply valve for flush tanks, comprising a cylindrical casting having a cylindrical portion provided with an opening and a downwardly disposed annular seat above and externally of said opening, a casing detachably secured to the casting and comprising a depending lower part and an upwardly projecting upper part, the latter having a passage in its upper end in line with the passage of the casting and also having a spout above the latter, a valve comprising a cylindrical plug fitting with a water-tight relation in the passage of the casting, a cup rigid with and surrounding said plug and externally embracing the cylindrical portion of the casting below said annular seat, a head fitting slidably in the passage of the upper portion of the casting, and a stem of less diameter than and connecting the plug and said head, a bell-crank lever pivoted to the upper part of the casting, a float secured to the outer end of said lever, a toggle-joint between the opposite end of said lever and the casing, and a link pivotally connecting the head of the valve and the pivotal point of connection of the members of said toggle-joint.

In testimony whereof I affix my signature, in the presence of two witnesses.

JAMES S. CALDWELL.
